UNITED STATES PATENT OFFICE

1,940,923

STRAINER

Joseph Stringer, Downingtown, Pa.

Application September 28, 1932
Serial No. 635,262

1 Claim. (Cl. 210—164)

This invention relates to a strainer designed particularly for straining liquid for spraying and pumping purposes and the like, and the prime object of the invention resides in the provision of a strainer of this nature which is non-collapsible.

Further objects of the invention are to provide a strainer of this nature which is simple in its construction, inexpensive to manufacture, easy to assemble and disassemble, thoroughly efficient and reliable in use, and otherwise well adapted to the purpose for which it is designed.

With the above and numerous other objects in view as will appear as the description proceeds, the invention consists in certain novel features of construction, and in the combination and arrangement of parts as will be hereinafter more fully described and claimed.

In the drawings:

Figure 1 is a longitudinal section through the structure showing the strainer per se in side elevation.

Figure 2 is a similar section showing the strainer per se also in section.

Figure 3 is a transverse section taken substantially on the line 3—3 of Figure 2.

Figure 4 is a perspective view of one plug.

Figure 5 is a perspective view of a tube.

Figure 6 is a perspective view of a cylindrical strainer.

Figure 7 is a perspective view of the other plug.

Referring to the drawings in detail, it will be seen that the numeral 5 denotes a cylindrical hollow body having a branch radiating outwardly from the central portion thereof denoted by the numeral 6. The branch 6 is internally threaded to receive a pipe 7.

The ends of the body are internally threaded to receive plugs 8 and 9. The plug 8 at its inner end is provided with a central recess 10 countersunk as at 11. The plug 9 is provided with an opening, the portion 12 thereof being threaded and the portion 14 thereof being countersunk, the portion 14 being located at the inner end of the plug, and the portion 12 located at the outer end of the plug.

A pipe 15 is engaged in the threaded end or portion 12. Numeral 16 denotes a perforated tube having an outwardly directed annular flange 17 at one end thereof to seat in the countersunk portion 14, the other end of the tube is seated in 60 the recess 10.

Numeral 18 denotes a cylinder of mesh material disposed about the tube 16 and having its upper end extending into the countersink 11 and the lower end thereof resting on the flange 17. 65

It is thought that the construction, utility, and advantages of this invention, will be now quite apparent without a more detailed description thereof.

The present embodiment of the invention has 70 been described in considerable detail merely for the purposes of exemplification since in actual practice it attains the features of advantage enumerated as desirable in the statement of the invention and the above description. 75

It will be apparent that changes in the details of construction, and in the combination and arrangement of parts may be resorted to without departing from the spirit or scope of the invention as hereinafter claimed or sacrificing any of 80 its advantages.

I claim:

A device of the class described comprising a cylindrical hollow body having a lateral branch extending outwardly therefrom, a plug threaded 85 in each end of the body, one plug having a countersunk recess in its inner end and the other plug having an opening therein provided with an outer threaded part for receiving an end of a pipe, an intermediate part of smaller diameter to 90 register with the bore of the pipe and an inner part of larger diameter than the threaded part, a perforated tube having a flange at one end fitting in the inner enlarged part of said opening with the other end of the tube fitting in the recess and 95 a cylindrical screen of larger diameter than the exterior diameter of the tube and encircling the tube and having one end resting on the flange and its other end fitting in the countersink of the recess. 100

JOSEPH STRINGER.
